METHOD OF AND APPARATUS FOR
TREATING WELLSOrmond Barstow, Midland, Mich., assignor to
The Dow Chemical Company, Midland, Mich.,
a corporation of Michigan

Application August 28, 1940, Serial No. 354,509

7 Claims. (Cl. 166—2)

The invention relates to a method of and apparatus for treating wells, such as oil, gas, brine, or water wells, and more particularly concerns a method whereby a fluid treating agent may be simultaneously introduced into two or more zones penetrated by the bore of a well while said zones are sealed off or separated from one another in such manner that the fluid agent in the well bore about to enter one zone is maintained out of contact with the fluid treating agent in the well bore about to enter the other zone.

The bore of a well oftentimes penetrates more than one producing stratum or zone, and it is usually desirable when treating such wells with a fluid treating agent to be assured that some of the treating fluid will be injected into each zone. In some instances it is even desirable to closely control the amount of treating fluid that is injected into each zone. For example, in the treatment of more than one productive zone in calcareous earth or rock to bring about an increase in production by the use of an acid, it may be desirable that a method of treatment be provided to positively insure that each zone will receive a definite proportion of the acid, for otherwise most of the acid may drain into the zone having the most porous structure, with the result that the most effective increase in production will not be obtained from the section or sections having the smaller pore spaces or voids. It is further desirable, when treating such wells, that the introduction of fluid agent into each zone take place simultaneously in order to avoid carrying out a separate treatment of each zone.

The term "zone," used herein and in the appended claims, refers to separately defined strata as well as sections or portions of a single stratum or formation.

It is, therefore, the principal object of the invention to provide a method and apparatus whereby a fluid treating agent may be simultaneously introduced into each of at least two zones penetrated by the bore of a well.

Another object of the invention is to provide a method and apparatus whereby a fluid treating agent may be simultaneously introduced into at least two zones at a preselected ratio of rates of flow.

Other objects and advantages will be apparent as the description of the invention proceeds.

The invention, then, resides in the method hereinafter more fully described and particularly pointed out in the claims, the accompanying drawings and following description setting forth in detail a mode of carrying out the invention,

such mode illustrating, however, but one of the several ways in which the invention may be put into operation.

In the accompanying drawings:

5 Fig. 1 is a fragmentary view of a well bore in vertical cross-section showing one embodiment of the invention.

10 Fig. 2 is a fragmentary sectional view of Fig. 1 showing that section of conduit 9 which includes the discharge port 10 and illustrates additional elements associated with the discharge port, which act to modify the operation of the apparatus.

15 Fig. 3 is a fragmentary view of a well bore in vertical cross-section showing another embodiment of the invention which may be suitably used in place of the apparatus illustrated in Fig. 1.

20 Fig. 4 is a cross-sectional view taken along the lines 4—4 of Fig. 3 looking in the direction of the arrows.

Referring more in detail to Fig. 1, the upper portion of the well bore is cased with metal pipe 1, which is cemented in place about its lower end by cement 2. The lower portion 3 of the well bore penetrates a productive stratum 4, an impervious stratum 5, and ends in a second productive stratum 6. Attached to the well tubing 7 by means of a coupling 8 a short conduit 9 is shown provided with a discharge port 10 at a point adjacent the upper productive stratum 4. The lower portion of conduit 9 ends in an inwardly projecting flange 11, which serves as a seat for the body member 12 housing the fluid flow control element. The body member 12 of the control element is provided with an outwardly projecting flange 14, which engages inwardly projecting flange 11 of conduit 9 and is securely held thereto by means of bolts 13. The housing of the control element comprises two separate symmetrical sections, which are secured to each other at flanges 15 by bolts 16. In addition, flanges 15 and bolts 16 act to support and hold diaphragm 17 in position so that it divides the body member of the control element into two compartments. The diaphragm 17 is of corrugated or bellows-like construction and is thus adapted to move laterally as pressure in one compartment builds up in excess of that in the other compartment. The diaphragm 17 is provided on either face with centrally located tapered plug members 18, which are adapted to engage complementally tapered shoulders on the fluid outlet or discharge ports 19 and 20, so as to partially seal off the flow of fluid from either compartment through said discharge ports as the diaphragm 17 moves laterally

in either direction. The plug members 18 are provided with guide pins 21 which act to properly direct the plug members 18 into engagement with the tapered shoulders on the discharge ports. The housing of the control element is also provided with threaded bosses 22 and 23 into which threaded orifice members 24 and 25 screw, serving as inlet ports for the fluid entering the left and right compartments of the control element. Discharge port 19 in the left compartment of the control element communicates with the well bore through conduit 26; while discharge port 20, provided in the right compartment, communicates through conduit 27 with the interior of tubular element 28 attached to the lower end of conduit 9 by means of conventional coupling or collar, indicated by numeral 8. The tubular element 28 extends into the well and acts to support conventional packer 29, shown in seated engagement with the well bore against impervious stratum 5. Below the packing element, tubular element 28 extends further into the well and is sealed off with cap 30 at its lower end. The tubular member 28 is provided with a port 31 below the packing element 29, which serves as a means whereby fluid may enter the well bore from the interior of the conduit below the packer.

In the fragmentary sectional view shown in Fig. 2, the discharge port 10 of Fig. 1 is shown equipped with a back pressure valve assembly. Housing 32 of the valve assembly is attached to the wall of conduit 9, as by welding. The valve assembly consists of a housing 32 having ports 33 and well 34, in which valve stem 35 slides as pressure applied interiorly of conduit 26 overcomes the pressure of the spring 36, acting to force the valve out of sealing relationship against discharge port 10.

In the embodiment shown in Fig. 3, the well tubing 7 extends into the well and engages a conventional coupling 8. The coupling serves to attach well tubing 7 to a short tubular element 37, which acts as a housing for a fluid flow control assembly adapted to accomplish the same results as the apparatus of Fig. 1. The tubular element 37 is provided at its upper end with a plate 38 having threaded bosses 39 and 40, which engage removable orifice plug members 41 and 42. The plate 38 is secured and sealed about its peripheral edge to the tubular element 37, as by means of a weld. The lower end of tubular element 37 is likewise provided with a plate 43 having discharge outlets 44 and 45, and is secured to tubular element 37 in a manner similar to that of the upper plate, as by welding. Within the compartment formed by the two plates 38 and 43 and tubular member 37, a short cylindrical tube 46 rests on plate 43 and acts as a cylinder in which piston 47 is adapted to slide. The cylinder or tube 46 rests on the plate 43 and is securely held thereon by means of plate 48 extending in a direction transverse of that of the cylinder, as shown more particularly in Fig. 4. The plate 48 is sealed and secured to the tubular element 37 and plate members 38 and 43, as well as cylinder 46, by welding, and thus divides the interior of tubular element 37 into two compartments. Set screws 49 threadedly engage bosses 50 in either wall of tubular element 37 at points opposite the ends of piston 47, and act as stop members for the piston as it slides in the cylinder 46. The cylinder 46 is provided with discharge ports 51 and 52, which are adapted to register with ports 44 and 45 in the lower plate member 43. The discharge port 45, communicat-

ing with the left compartment of the control element, discharges through conduit 53 and port 54 into the well bore at a point adjacent the productive stratum 4. The port 44, communicating with the right compartment of the control element, allows the fluid to flow into conduit 55, and thus into the stratum below the packer. Conduit 55 acts to support conventional packing element 29, also shown in Fig. 1, which is in seated engagement with impervious stratum 5. Below the packing element the conduit 55 extends further into the well and ends in conventional cap member 56. A port 57 is provided in conduit 55 below the packing element 29, and serves as a means whereby the fluid discharging from the right compartment of the control element can flow into lower productive stratum 6.

In Fig. 4 the relation of plate member 48 and the associated piston and cylinder is more clearly shown.

The method of the invention will be best understood from the following description, wherein the apparatus illustrated in Fig. 1 is employed to carry out an acid treatment for the simultaneous injection of acid into strata 4 and 6. With the apparatus assembled as shown, well tubing 7 is lowered into the well bore so as to position the packing element opposite the impervious stratum 5. The packer is then seated so as to separate productive stratum 4 from productive stratum 6, and a quantity of acid (not shown) is introduced into the well through the tubing 7. Pressure is then applied to the acid, as by pumping an additional quantity of acid into the well through the tubing 7. At the same time, if desired, oil may be introduced into the annular space exterior of the well tubing, so as to control the level to which the acid solution can rise in the well bore as it escapes from the discharge port 10 in conduit 9. Acid entering the conduit 9 is directed into each compartment of the control element through the inlet ports in orifice members 24 and 25. The fluid agent entering the left compartment is forced therefrom through port 19, conduit 26 and port 10 into the well bore adjacent stratum 4. The fluid entering the right compartment of the control element is forced therefrom through discharge port 20 and conduit 27 into conduit 28, and thereafter out into the well bore below the packer through port 31. The orifice size in inlet orifice members 24 and 25 is conveniently chosen so that a pressure drop can readily be maintained across the orifices during the introduction of the fluid agent. By varying the diameter of the orifices, more or less acid can, of course, be directed to a selected zone. After the desired quantity of acid has been introduced, it may be displaced from the interior of the well tubing and conduit 9 by pumping a quantity of oil or the like into the well through said tubing.

During the introduction of the fluid agent, the control assembly functions to regulate the rate of flow of fluid by directing fluid to each stratum at a rate approximately proportional to the cross-sectional area of the orifices or ports 24 and 25 in the orifice members, since the pressure in the two compartments is maintained substantially equal at all times during the treatment by the diaphragm actuated plug members. For example, if at any time during the introduction of the fluid agent one stratum requires a higher pressure to force fluid thereinto at the rate it is being delivered by the respective orifices, pressure will build up in the compartment associated with the stratum requiring the application of the

highest pressure to force fluid thereinto, causing the diaphragm actuated plug members to partially seal the discharge outlet in the other compartment, so as to bring about an equalization of pressure in the two compartments. Since the pressures in the two compartments, and therefore the pressure-drops across the two orifices, are at all times substantially equal, the ratio of rates of flow to the two strata is substantially equal to the ratio of areas of the inlet orifices 24 and 25. This fixed ratio of flow rates to the two strata can be set at a predetermined value by installing orifices 24 and 25 having the desired area ratio in the control apparatus before it is placed in the well. The discharge ports or outlets should be made relatively large in comparison to the inlet orifices so that pressure will not build up in the compartments of the control assembly due to the fact that the area of the outlets are restricted relative to the inlets. It is desirable to select the inlet orifices of such a size that it is possible to readily maintain a pressure drop across them of such order that the piston or diaphragm operated plug members will be actuated to control the flow of fluid.

If desired, the spring loaded back pressure valve assembly illustrated in Fig. 2 may be employed by attaching said assembly to either of the fluid discharge outlets. The back pressure valve assembly or the like, associated with the discharge ports or outlets, may be advantageously used in some instances, as for example, to correct for differences in formation pressure between the various zones that may be encountered. Such correction maintains each compartment of the control element at more nearly equal pressures, allowing the diaphragm or piston to take a more central position than they otherwise could where wide differences in pressure exist between the various zones.

Similarly, the method of the invention may also be suitably carried out employing the modification illustrated in Fig. 3, which is also adapted to direct fluid to each stratum at a rate directly proportional to the diameter of the fluid inlet orifices. In the apparatus illustrated in Fig. 3, the piston 47 functions in a somewhat similar manner to the diaphragm member carrying the plug members illustrated in Fig. 1. For example, when the fluid pressure becomes greater in one compartment than the other, the piston moves to relieve the pressure, and, by partially sealing off one of the discharge outlets, acts to equalize the pressure so that the same pressure exists in both compartments. This in turn insures that fluid will flow to each stratum at a rate directly proportional to the size of the orifice communicating therewith, since the pressure drop across the two orifices is kept equal.

The method will be found to have most general use in connection with an acid treatment wherein a solution of hydrochloric or other acid is introduced into the formation to bring about solution of the earth or rock formation and thus an increase in size of the flow channels through which the desired mineral fluid flows to the well. In such treatments it will usually be found preferable to employ an aqueous solution of hydrochloric acid of from 5 to 25 per cent concentration. If desired, such an acid may be inhibited against corrosive attack upon iron or steel in the manner taught in U. S. Patent No. 1,877,504.

Although the method has been described with particular reference to an acid treatment, it is to be understood that any fluid treating agent may

be introduced in accordance with the method of the invention. Examples of such treating agents are paraffin solvents, liquid sealing agents, and the like.

5 In the above manner a fluid treating agent such as an acid may be simultaneously introduced into two or more strata or zones with the assurance that each formation will receive a more satisfactory treatment than is the case if the conventional method is employed wherein the bore hole is merely filled with the treating fluid and pressure applied thereto to force the treating fluid into each stratum at a rate dependent only upon the ability of the formation to receive the fluid agent.

15 I claim:

1. In a well treating device for the simultaneous injection of a fluid agent into at least two zones penetrated by the bore of a well, the combination of a conduit adapted to be disposed in the well bore, sealing means surrounding said conduit adapted to seal the annular space between the conduit and the well bore at a point between said zones, fluid control means carried by the conduit having restricted fluid entry ports and discharge ports therein, with the discharge ports in communication with the zones above and below the sealing means, said control means being adapted to maintain substantially equal pressures at the discharge ports so as to direct the fluid agent to each zone at a substantially fixed ratio of rates of flow.

2. In a well treating device for the simultaneous introduction of a fluid agent into at least two zones penetrated by the bore of a well, the combination of a conduit having spaced openings therein, sealing means surrounding said conduit between said openings and adapted to seal the annular space between the conduit and the well bore at a point between said zones, a fluid flow control device sealed in said conduit having restricted ports for the entry of fluid into the interior thereof and fluid discharge ports which communicate with the spaced openings in the conduit above and below the sealing means, a movable member dividing the fluid flow control device into two compartments sealed from each other so that a restricted fluid entry port and a fluid discharge port communicate with each compartment, said movable member being adapted to engage the fluid discharge ports in sealing relationship as the movable member is caused to move in response to pressure building up in one compartment in excess of that in the other compartment.

3. In a well treating device for the simultaneous injection of a fluid agent into at least two zones penetrated by the bore of a well, the combination of a conduit having spaced openings therein, sealing means surrounding said conduit at a point between the openings adapted to seal the annular space between the conduit and the well bore at a point between said zones, a fluid flow control means sealed in said conduit having restricted ports for entry of fluid into the interior thereof and fluid discharge ports communicating respectively with the spaced openings in the conduit above and below the sealing means, a movable diaphragm member dividing the interior of the control element into two compartments sealed from each other so that a fluid entry port and a fluid discharge port communicate with each compartment, and a plug member carried by the movable diaphragm adapted to engage the fluid discharge ports in sealing relationship as the diaphragm is caused to move laterally by the

pressure building up in one compartment in excess of that in the other compartment.

4. In a well treating device for the simultaneous injection of a fluid agent into at least two zones penetrated by the bore of a well, the combination of a conduit means adapted to be disposed in the well bore, sealing means surrounding said conduit adapted to seal the annular space between the conduit and the well bore, fluid control means associated with said conduit having restricted ports for the entry of fluid into the interior thereof and fluid discharge ports communicating respectively with the zones above and below the sealing means, said fluid control means being adapted to respond to the pressure required to force the fluid agent into each zone so as to direct the fluid into each zone at a rate substantially proportional to the area of the restricted entry ports.

5. In a well treating device for the simultaneous injection of a fluid agent into at least two zones penetrated by the bore of a well, the combination of a conduit having spaced openings therein, sealing means surrounding said conduit adapted to seal the annular space between the conduit and the well bore at a point between the openings, a fluid flow control device sealed in said conduit having restricted ports for the entry of a fluid into the interior thereof and fluid exit ports communicating respectively with spaced openings above and below the sealing means, a plate member dividing the interior of the control element into two compartments, a piston disposed

in an opening in said plate member adapted to move in said opening so as to curtail the flow of fluid to one of the exit ports as the piston is caused to move by pressure building up in one compartment in excess of that in the other compartment.

6. The apparatus of claim 1, wherein a spring loaded back pressure valve is associated with one of the spaced openings in the conduit.

7. In a well treating device for the simultaneous injection of a fluid agent into at least two zones penetrated by the bore of a well, the combination of a conduit having spaced openings therein, sealing means surrounding said conduit adapted to seal the annular space between the conduit and the well bore at a point between the openings, an enclosed fluid flow control element sealed in said conduit having restricted ports for the entry of a fluid into the interior thereof and fluid exit ports communicating respectively with spaced openings above and below the sealing means, a piston disposed in the control element and dividing the interior thereof into two compartments so that a fluid entry port and fluid exit port communicate with each compartment, said piston being adapted to move in the control element to engage the fluid exit ports in sealing relationship without sealing the fluid entry ports as the piston moves by pressure building up in one compartment in excess of that in the other compartment.

ORMOND BARSTOW.
